UNITED STATES PATENT OFFICE.

ARTHUR WENDLINGER, OF RICHMOND, VIRGINIA.

DOOR-CHECK.

952,854.

Specification of Letters Patent. Patented Mar. 22, 1910.

Application filed June 9, 1909. Serial No. 501,116.

To all whom it may concern:

Be it known that I, ARTHUR WENDLINGER, a citizen of the United States of America, and resident of Richmond, in the county of Henrico and State of Virginia, have invented certain new and useful Improvements in Door-Checks, of which the following is a specification.

This invention relates to certain new and useful improvements in door checks of that class which are applied to the rabbet of a door and designed to prevent noise or vibration as the door is closed.

The present invention is applicable to any and all kinds of closures, doors, windows or the like, and will be found especially beneficial in hospitals, sanatoriums, sleeping cars and other places where the noise and jar occasioned by the shutting of a door or window is annoying to the patient or to the party occupying the room or apartment in which the door is located. Heretofore, it has been proposed to lessen or prevent the noise and vibration by various means which, so far as I am aware, have not gone into practical use for the reason that they were not well adapted for the purpose. The elastic buffer was liable to injury, and, if loosely and removably inserted within its opening in the jamb or other part, was liable to be pulled out and become lost. Where a metallic case has been employed for enveloping the buffer, the same has been fixed and not movable with the buffer and did not serve as a means to prevent cutting or wearing away of the buffer in use.

The primary object of my invention is to provide simple and efficient means for overcoming the above objections and for insuring a positive doing away with the noise and jar or vibration and permitting of a tight closing of the door or window and insuring against pulling out of the buffer by the suction caused by the opening of the door.

Other objects and advantages of the invention will hereinafter appear and the novel features thereof will be particularly pointed out by the appended claims.

The invention, in some of its preferred forms, is clearly illustrated in the accompanying drawings, which, with the numerals of reference marked thereon, form a part of this specification, and in which—

Figure 1 is a detail in elevation showing a portion of a door frame or jamb with one

of my improved buffers applied. Fig. 2 is an enlarged sectional detail showing a portion of the frame and the door, the latter being in its closed position against the buffer. Fig. 3 shows, in longitudinal section and end elevation, one of the buffers. Fig. 4 shows, in side elevation and end view, another form of buffer. Fig. 5 shows, in longitudinal section and end elevation, the form of buffer seen in Fig. 4, with a metallic protector.

Like numerals of reference indicate like parts throughout the several views.

Referring to the drawings, 1 designates a portion of a door frame or jamb and 2 a section of a door. In the rabbet 3 of the frame or jamb, I bore or otherwise form one or more openings 4, generally one near the top and one near the bottom, and, in some instances, one or more intermediate these points. A showing of one, however, in this instance, is deemed sufficient to give a clear understanding of the invention. Into these openings, I place elastic buffers, preferably of a good quality of india rubber. In Fig. 2, the hole or opening 4 is shown as countersunk at its outer end, as seen at 5, and in this is removably inserted the shank 6 of the buffer 7, which is provided with an enlarged or head portion 8 fitted to the countersink, the bottom wall of which may or may not be beveled. If beveled, as shown in Fig. 2, the coating portion of the buffer, that is, that at the junction of its shank and head, will be correspondingly beveled, as shown at 9. The opening is of greater depth than the length of the buffer so as to allow of end-wise compression, and, in order to allow the buffer to expand laterally at its head portion and further to permit of the sufficient compression thereof to allow of a tight closing of the door, I form the outer face of the head with a concavity, as seen at 10, which permits of the head portion being compressed practically within its countersink, although normally projecting beyond the outer face of the rabbet, and, in order to allow of the escape of the air that may be confined within this concavity and prevent any possibility of the suction withdrawing the buffer, I provide the outer rim 11 with a plurality of notches or the like 12 which readily allow of the escape of the air confined within the concavity when the door is closed so that, when the door is opened, there will be no suction between the con-

caved head of the buffer and the contacting portion of the door.

It will be readily understood that, when the door is closed, the buffer prevents contact of wood with wood, the door closing against the outer face of the buffer and all noise and jar or vibration are obviated. The buffer is free to be compressed longitudinally and laterally within its opening, being unconfined and hence less compression is required in order to insure a tight closure between the door and its jamb or frame.

In Fig. 4, I have shown another form of buffer constructed to allow of longitudinal and lateral compression or expansion. In this form, the buffer 13 is of india rubber or the like and has a convex head portion 14 to prevent suction between the same and the door, and intermediate its ends it is circumferentially reduced in diameter, as seen at 15. This is inserted within a correspondingly shaped opening in the jamb and is free to move bodily therein. When the door is brought in contact therewith, it is compressed endwise within its opening, this movement being permitted by reason of the reduced or cut-away intermediate portion, and, when the pressure is removed from the door, the buffer expands and assumes its normal position. In order to prevent cutting or scraping of the buffer by contact with the walls of the opening in the jamb in which it is located, I sometimes provide the buffer 13 with a protector 16, preferably of metal, which embraces the portion 17 of said buffer and is confined thereabout in any suitable manner, as by crimping or pressing inward its opposite edges, as seen at 18 in Fig. 5. This buffer, like the others, is free to move bodily within its opening in the jamb, and, the protector 16 coming in contact with the walls of the opening, prevents all liability of injury to the buffer. It is to be noted that the convex outer face of the

buffer projects beyond the protector so as to avoid any possibility of contact of the protector with the door.

The advantages of the construction hereinbefore described will be appreciated especially by those who have been annoyed while sick by the noise and vibration caused by the slamming or closing of the door not provided with means for preventing the same.

What I claim as new is:—

1. An elastic buffer bodily movable within an opening in a frame and free to be compressed longitudinally and laterally and having a shank and an enlarged head portion with concaved outer face.

2. An elastic buffer having a shank and an enlarged head portion with concaved outer face and a marginal rim having passages communicating with said concavity.

3. The combination with a door and its frame, of a countersunk opening in the rabbit of the frame, and an elastic buffer having a shank received within said opening and an enlarged head receivable in the countersink, said shank and head being freely bodily movable in said opening and countersink for expansion longitudinally and laterally.

4. The combination with a door and its frame, of a countersunk opening in the rabbit of the frame, and an elastic buffer having a shank received within said opening and an enlarged head receivable in the countersink, said head having a concavity in its outer face and a surrounding rim having passages for the escape of the air from said concavity.

Signed by me at Washington, D. C., this 9 day of June 1909.

ARTHUR WENDLINGER.
